Primary Examiner — Melanie H Tung

(74) Attorney, Agent, or Firm — Banner & Witcoff, Ltd.

(57) **CLAIM**

The ornamental design for a display screen with icon, as shown and described.

DESCRIPTION

FIG. 1 is a front view of a display screen with icon showing our new design; and,

FIG. 2 is a front view of a display screen with icon showing an alternative embodiment of our new design in FIG. 1.

The broken line showing of the display screen forms no part of the claimed design.

1 Claim, 1 Drawing Sheet
